[57] **CLAIM**

The ornamental design for a table lamp, as shown and described.

DESCRIPTION

FIG. 1 is a perspective view of the table lamp showing my new design;

FIG. 2 is a right side elevational view of the table lamp, the left side elevational view being a mirror image;

FIG. 3 is a front elevational view of the table lamp;

FIG. 4 is a rear elevational view of the table lamp;

FIG. 5 is a top plan view of the table lamp; and,

FIG. 6 is a bottom plan view of the table lamp.

The shade shown in broken lines is for illustrative purposes only and forms no part of the claimed design.
